NEGLIGEE

Naseeb Malouf, New York, N.Y.

Application September 22, 1958, Serial No. 52,709

Term of patent 7 years

(Cl. D3—26)

Fig. 1 is a front view of a negligee, showing my new design; and

Fig. 2 is the rear view thereof.

The characteristic feature of my design resides in the specific rounded yoke member comprising bias folds of self-fabric interlaced with ribbons, in combination with the negligee disclosed.

I claim:

The ornamental design for a negligee, substantially as shown and described.
